UNITED STATES PATENT OFFICE

92,865

DESIGN FOR A SHOE

Charles Morali, Forest Hills, N. Y.

Application April 14, 1934, Serial No. 51,408

Term of patent 3½ years

To all whom it may concern:

Be it known that I, CHARLES MORALI, a citizen of the United States, residing in Forest Hills, Long Island, in the county of Queens and State of New York, have invented a new, original, and ornamental Design for a Shoe, of which the following is a specification, reference being had to the accompanying drawing, forming part thereof.

I claim:

The ornamental design for a shoe, as shown.

CHARLES MORALI.
